(57) **CLAIM**

The ornamental design for a water float toy, as shown and described.

DESCRIPTION

FIG. 1 is a front and side perspective view of our new water float toy;

FIG. 2 is a front elevation view thereof, the side and rear elevation views being identical thereto;

FIG. 3 is a top plan view thereof; and,

FIG. 4 is a bottom plan view thereof. The broken lines in FIG. 4 are included for the purpose of illustrating a portion of the water float toy that forms no part of the claimed design.

The appearance within the unshaded circular area of FIG. 4 forms no part of the claimed design.
